2,491,530

HARD SURFACE WALL AND FLOOR
COVERINGWarren Stubblebine, Lancaster, Pa., assignor to
Armstrong Cork Company, Lancaster, Pa., a
corporation of Pennsylvania

Application November 30, 1944, Serial No. 565,908

10 Claims. (Cl. 20—7)

1

This invention relates to hard surface wall and floor coverings. More specifically, it is concerned with a floor or wall covering including a stratum of partible, felted, fibrous material. Such coverings consist essentially of a body made of felted fibers impregnated with a water-resistant material, such as asphalt, and having a decorative paint coat or a layer of linoleum composition as a wearing surface.

A serious defect of this type of floor covering resides in the fact that it is not ordinarily feasible to adhesively secure the same to a floor or wall. It is desirable to adhesively secure the covering into place; so far as walls are concerned, it is impracticable to use coverings of this type unless they can be adhesively secured. So far as floors are concerned, adhesively securing the covering to the floor is desirable because it prevents scuffing or cracking of the material, curling of its edges, buckling, and the like.

The obvious advantages involved in adhesively securing the covering in place have been recognized but the practice has been avoided because of the difficulties which ensue if removal of the covering be subsequently attempted. As a practical matter, the user of such coverings will wish to replace the covering, even if only at infrequent intervals.

The impregnated fibrous covering is inherently less resistant to rupture than any of the adhesives customarily used in the floor or wall covering art. The material, due to the felting operation, is laminar in character and tends to pull apart at different levels between the top and bottom surfaces depending upon a number of factors, such as the manner in which it is pulled from the floor, the uniformity of impregnation, the uniformity of the floor, etc. If it is attempted to remove a piece of adhesively secured felt base, the covering itself is destroyed and the floor is left with an ugly and irregular covering of adhesive and pieces of asphalt saturated felt. It is impossible to deal with such a condition satisfactorily.

These difficulties may be overcome and such coverings by the use of my invention may be adhesively secured to walls or floors and subsequently removed in such a way as to leave the wall or floor in condition to receive another covering without destruction of the original covering which has been removed. These results are attained by interposing between the stratum of partible, felted, fibrous material and the wall or floor a rupturable fibrous layer composed of haphazardly scattered, heterogeneously dispersed fibers which are not interlocked or entangled to any substantial extent and which is materially weaker than the stratum of fibrous material in its resistance to rupture.

According to the preferred embodiment of my invention, the rupturable fibrous layer is com-

2

posed of cotton flock, cotton shearings, or carpet shearings. All of these materials retain fibrous characteristics, even in the form of flock. An adhesive coating is placed on the stratum of rupturable fibrous material and serves to bond the flock layer thereto. In addition, it may serve as a sealing coating for the impregnant of the fibrous stratum.

In the manufacture of the floor or wall covering of my invention, a decorative wear surface is integrally united with the partible, felted, fibrous stratum. The wear surface may comprise a paint coating as is customary in the manufacture of so-called felt base floor coverings or it may consist of an oxidized siccative oil-resin gel, such as linoleum composition, for example. The bonding and sealing coating is then placed on the opposite side of the partible stratum and the layer of cotton flock is formed thereon and adhesively secured to the stratum by the sealing and bonding coating. Preferably, the layer of cotton flock is formed by blowing the cotton flock onto the adhesive coating, although if desired, cotton flock may be distributed thereon by means of a vacuum roll or similar means.

It will be understood, if desired, the adhesive and sealing coating may be placed on the fibrous stratum before the wear surface is united therewith and later activated or rendered adhesive in any suitable manner to secure the flock layer to the fibrous stratum.

From my experiments, I have determined certain definite limits of cohesion within which the strength or resistance to tensile forces of the flock layer must fall in order to obtain ready removability. I have determined that limits of cohesion of 3 to 30 pounds are satisfactory, but limits of 6 to 30 pounds are preferred. With greater tensile resistance than 30 pounds, the flock layer is resistant to a degree to prevent ready removability. With tensile resistance less than 3 pounds, it is dangerously weak and the covering may be loosened from the base by severe traffic and excessive wear; for that reason, a minimum of 6 pounds is preferred.

The "pull" test, hereinafter referred to as the Scott test used to establish these limits, may be carried on in the following manner:

To one side of a strip of wood 6" long and 2" wide, a thin layer of linoleum cement or paste is applied using a notched doctor blade to apply the paste or cement evenly over the entire surface. To the paste or cement is immediately applied a strip of the covering to be tested 8" long and 2" wide, one end of which is placed flush with one end of the strip of wood, the other end extending freely beyond the wood strip. After rolling to obtain a satisfactory bond between the wood and the covering, the sample is maintained at normal room temperature for approximately

four days to dry the paste or cement. The resistance of the cotton flock layer to tensile forces is determined by placing the sample in a Scott tensile strength machine at right angles to the direction of the forces to be exerted. The strength of the forces recorded as the covering is removed from the wood strip measures the resistance of the flock layer to tensile forces.

Any suitable sealing and bonding coating may be used to secure the layer of cotton flock to the stratum of particulate fibrous material. I have found a satisfactory adhesive may be composed of equal parts of a mixture of a modified alkyd resin, such as "Paraplex" 5B and a solvent-soluble, chemically plasticized urea-formaldehyde resin, such as "Uformite" QR129. Any suitable solvent may be used as a vehicle for these resins. As I understand, "Uformite" QR129 is a heat-reactive, solvent-soluble urea-formaldehyde condensate plasticized with dicapryl phthalate.

It will be understood the layer of cotton flock may be applied to the stratum of particulate fibrous material prior to application of the wear surface on the face thereof or the layer may be secured thereto after the wear surface has been integrally united therewith. With the rupturable flock layer of my invention, length of maturing time and temperatures of maturing of the wear surface are not important for they do not affect the rupturability characteristics of the cotton flock layer.

If desired, a sealing coating may be applied to the stratum of particulate fibrous material before the application of the adhesive coating. This is generally not necessary but it offers additional assurance that the impregnant of the particulate fibrous stratum is satisfactorily sealed therein.

While the present invention has been described as particularly adapted to the manufacture of so-called felt base and linoleum-like floor or wall coverings, it is likewise adapted for use in the production of coverings, such as industrial flooring which comprises a saturated felt base or body carrying an asphaltic coating as a wearing surface; floor coverings in which the base or body may form the wearing surface, or any similar floor coverings which include a particulate fibrous stratum, such as asphalt-saturated felt underlayment for resilient tiles and the like.

A building structure embodying my invention may be formed in the following manner: The base is prepared to receive a covering; that is, it is cleaned and levelled so that it presents a clean, dry, substantially smooth surface. A layer of adhesive is spread evenly over the base; the hard surface covering is laid thereon before the adhesive is dry and firmly pressed thereagainst as by rolling, placing heavy sand bags thereover, or the like. When the adhesive has dried, the covering is securely attached to the base.

When it is desired to remove the covering, the rupturable cotton flock layer may be readily ruptured by exerting tensile forces on the structure. When the covering is removed, the base may be readily placed in condition to receive a new covering by washing away the adhesive remaining thereon and following the process described above. In many cases, it is not essential to wash off the adhesive remaining on the base since a satisfactory bond may be secured merely by placing another adhesive coating thereon and securing a covering thereto. Preferably, the adhesive is removed since in some cases the adhesive may not be spread sufficiently smooth to permit a second adhesive coating thereover.

In the accompanying drawing illustrating my invention, Figure 1 is a sectional view of a building structure showing my hard surface covering secured to a base, a corner of the covering being raised to show the rupturable layer and the adhesive layer bonding the covering to the base; and Figure 2 is a sectional view, similar to Figure 1, illustrating a modification thereof.

Referring to the drawing, there is shown a base 10 2, a hard surface covering 3 comprising a wearing surface 4 preferably formed of an oxidized siccative oil-resin gel, a stratum of particulate fibrous material 5 which is impregnated by a waterproofing compound, such as asphalt, an adhesive layer 6 disposed on one side of the stratum 15 5, a layer of cotton flock 7 secured to the stratum 5 by means of the adhesive coating 6, and an adhesive layer 8 bonding the covering 3 to the base 2.

20 In Figure 2, I have shown a covering generally similar to that shown in Figure 1 except that a sealing coating 9 is interposed between the fibrous stratum 5 and the adhesive coating 6.

25 My invention presents numerous advantages. The floor or wall covering of my invention possesses definite removable features which are not affected by the temperatures or length of time required for maturing the wear surface. The rupturable layer may be easily and quickly applied 30 to the fibrous stratum forming the backing of the floor covering in an inexpensive manner. The rupturable floor covering of my invention is inexpensive and may be quickly and easily applied in position to form the decorative wear-resistant 35 surface of a floor or wall. In addition, the type and quantity of adhesive used to secure the covering to the base does not affect the rupturability characteristics of my floor covering to any substantial extent.

40 While I have described and illustrated a preferred embodiment of my invention, it will be understood my invention is not limited thereto since it may be otherwise embodied within the scope of the following claims.

45 I claim:

1. As a new article of manufacture, a hard surface wall or floor covering including a stratum of particulate, felted, fibrous material impregnated with a moisture-resistant substance and a rupturable 50 fibrous flocked layer adhesively secured to one side of said stratum, said rupturable fibrous layer being composed of haphazardly scattered, heterogeneously dispersed fibers which are not interlocked or entangled to any substantial extent and being materially weaker than the stratum of fibrous material in its resistance to rupture whereby when the covering is adhesively secured to a base with the layer interposed between the fibrous stratum and the base, the layer may be subsequently ruptured to permit removal of the covering from the base without rupture of the particulate stratum.

2. As a new article of manufacture, a hard surface wall or floor covering including a stratum of particulate, felted, fibrous material impregnated with a moisture-resistant substance and a rupturable fibrous flocked layer having a resistance to rupture in the range of 3 to 30 pounds as determined by the "Scott" test adhesively secured 65 to one side of said stratum, said rupturable fibrous layer being composed of haphazardly scattered, heterogeneously dispersed fibers which are not interlocked or entangled to any substantial extent and being materially weaker than the 70 stratum of fibrous material in its resistance to 75

rupture whereby when the covering is adhesively secured to a base with the layer interposed between the fibrous sheet and the base, the layer may be subsequently ruptured to permit removal of the covering from the base without rupture of the partible stratum.

3. As a new article of manufacture, a hard surface wall or floor covering including a decorative wear surface, a stratum of partible, felted, fibrous material impregnated with a moisture-resistant substance, and a rupturable fibrous flocked layer adhesively secured to one side of said stratum, said rupturable fibrous layer being composed of haphazardly scattered, heterogeneously dispersed fibers which are not interlocked or entangled to any substantial extent and being materially weaker than the stratum of fibrous material in its resistance to rupture whereby when the covering is adhesively secured to a base with the layer interposed between the fibrous stratum and the base, the layer may be subsequently ruptured to permit removal of the covering from the base without rupture of the partible stratum.

4. As a new article of manufacture, a hard surface wall or floor covering including a decorative wear surface comprising a siccative oil-resin gel, a stratum of partible, felted, fibrous material impregnated with a moisture-resistant substance integrally united with said wear surface, and a rupturable fibrous flocked layer adhesively secured to the opposite side of said stratum, said layer having a resistance to rupture in the range of 3 to 30 pounds as determined by the "Scott" test and being composed of haphazardly scattered, heterogeneously dispersed fibers which are not interlocked or entangled to any substantial extent, said layer being materially weaker than the stratum of fibrous material in its resistance to rupture whereby when the covering is adhesively secured to a base with the layer interposed between the fibrous sheet and the base, the layer may be subsequently ruptured to permit removal of the covering from the base without rupture of the partible stratum.

5. As a new article of manufacture, a hard surface wall or floor covering including a decorative wear surface comprising a siccative oil-resin gel, a stratum of partible, felted, fibrous material impregnated with a moisture-resistant substance integrally united with said wear surface, a sealing and bonding coating placed on one side of said fibrous stratum, and a layer of cotton flock secured to said stratum by said bonding coating, said layer of cotton flock having a resistance to rupture in the range of 3 to 30 pounds as determined by the "Scott" test and being materially weaker than the stratum of fibrous material in its resistance to rupture whereby when the covering is adhesively secured to a base with the layer of cotton flock interposed between the fibrous stratum and the base, the cotton flock layer may be subsequently ruptured to permit removal of the covering from the base without rupture of the partible stratum.

6. An article of manufacture according to claim 5 in which the sealing and bonding coating is composed of a mixture of a modified alkyd resin and a plasticized urea-aldehyde resin.

7. In a building structure, the combination of a base, and a wear-resistant floor or wall covering adhesively secured to said base, said floor or wall covering including a stratum of partible, felted, fibrous material impregnated with a moisture-resistant substance, and a rupturable fibrous flocked layer adhesively secured to the side of

said stratum adjacent the base, said rupturable fibrous layer being composed of haphazardly scattered, heterogeneously dispersed fibers which are not interlocked or entangled to any substantial extent and being materially weaker than the stratum of fibrous material in its resistance to rupture whereby the layer may be subsequently ruptured to permit removal of the covering from the base without rupture of the partible stratum.

8. In a building structure, the combination of a base, a floor or wall covering adhesively secured to said base, said covering including a stratum of partible, felted, fibrous material impregnated with a moisture-resistant substance, and a rupturable fibrous layer having a resistance to rupture in the range of 3 to 30 pounds as determined by the "Scott" test adhesively secured to the side of said stratum adjacent the base, said rupturable fibrous flocked layer being composed of haphazardly scattered, heterogeneously dispersed fibers which are not interlocked or entangled to any substantial extent and being materially weaker than the stratum of fibrous material in its resistance to rupture whereby the layer may be subsequently ruptured to permit removal of the covering from the base without rupture of the partible stratum.

9. In a building structure, the combination of a base, a floor or wall covering disposed over said base, and an adhesive layer bonding the covering to the base, said covering including a decorative wear surface composed of a siccative oil-resin gel, a stratum of partible, felted, fibrous material impregnated with a moisture-resistant substance, and a rupturable fibrous flocked layer having a resistance to rupture in the range of 3 to 30 pounds as determined by the "Scott" test adhesively secured to the side of said stratum adjacent the base and being composed of haphazardly scattered, heterogeneously dispersed fibers which are not interlocked or entangled to any substantial extent, said layer being materially weaker than the stratum of fibrous material in its resistance to rupture whereby the layer may be subsequently ruptured to permit removal of the covering from the base without rupture of the partible stratum.

10. In a building structure, the combination of a base, a floor or wall covering disposed over said base, and an adhesive layer bonding the covering to the base, said covering including a decorative wear surface comprising a siccative oil-resin gel, a stratum of partible, felted, fibrous material impregnated with a moisture-resistant substance, a sealing and bonding coating placed on one side of said fibrous stratum and a layer of cotton flock secured to said stratum by said bonding coating, said layer of cotton flock being materially weaker than the stratum of fibrous material in its resistance to rupture whereby the cotton flock layer may be subsequently ruptured to permit removal of the covering from the base without rupture of the partible stratum.
